US00D968761S

(12) **United States Design Patent** (10) Patent No.: **US D968,761 S**
(45) Date of Patent: ** *Nov. 8, 2022

(54) **WHOLE BODY WEARABLE BLANKET**

(71) Applicant: **Cozy Comfort Company LLC**,
Pleasanton, CA (US)

(72) Inventors: **Brian Speciale**, Cave Creek, AZ (US);
Michael Speciale, Phoenix, AZ (US)

(*) Notice: This patent is subject to a terminal disclaimer.

(**) Term: **15 Years**

(21) Appl. No.: **29/775,218**

(22) Filed: **Mar. 22, 2021**

Related U.S. Application Data

(63) Continuation-in-part of application No. 29/731,086, filed on Apr. 11, 2020, which is a continuation-in-part of application No. 29/705,878, filed on Sep. 16, 2019, now Pat. No. Des. 903,237, which is a continuation-in-part of application No. 29/645,978, filed on Apr. 30, 2018, now Pat. No. Des. 886,416, which is a continuation-in-part of application No. 29/617,421, filed on Sep. 13, 2017, now Pat. No. Des. 859,788.
